[57] CLAIM

The ornamental design for a lawn sprinkler, as shown and described.

DESCRIPTION

FIG. 1 is a perspective view of a lawn sprinkler showing my new design;

FIG. 2 is a top plan view thereof;

FIG. 3 is a right side elevational view thereof;

FIG. 4 is a bottom plan view thereof;

FIG. 5 is a rear elevational view thereof; and

FIG. 6 is a front elevational view thereof.

The broken line representation of indicia in FIGS. 1 and 6 are for illustration only.
